CLAIM

The ornamental design for a cosmetic package, as shown and described.

DESCRIPTION

FIG. 1 is a top perspective view of a cosmetic package showing our new design;

FIG. 2 is a front view of the cosmetic package of FIG. 1;

FIG. 3 is a rear view of the cosmetic package of FIG. 1;

FIG. 4 is a left side view of the cosmetic package of FIG. 1;

FIG. 5 is a right side view of the cosmetic package of FIG. 1;

FIG. 6 is a top view of the cosmetic package of FIG. 1;

FIG. 7 is a bottom view of the cosmetic package of FIG. 1; and,

FIG. 8 is a top perspective view of the cosmetic package of FIG. 1, with a cap thereof in an open position.

The portions of the cosmetic package shown in broken lines form no part of the claimed design.
